BRAKE BEAM SUPPORT AND SAFETY DEVICE

Filed May 4, 1927

INVENTOR

Louis G. Miller.

R. S. C. Dougherty

ATTORNEY

UNITED STATES PATENT OFFICE

LOUIS G. MILLER, OF BETHLEHEM, PENNSYLVANIA, ASSIGNOR TO BETHLEHEM STEEL COMPANY

BRAKE-BEAM SUPPORT AND SAFETY DEVICE

Application filed May 4, 1927. Serial No. 188,646.

My invention relates in general to car trucks and more particularly to trucks of the four wheel type, wherein the brakes are forced upon the tread of each of its four wheels simultaneously from both sides of the 5 transverse center of the truck.

The primary object of my invention relates more especially to trussed brake-beams and to a four point suspension for supporting the 10 brake-beams at their intermediate points. The features constituting the four point suspension consist, in addition to the customary 15 links or hangers which are connected to the brake-beam heads, not shown, and attached to the truck side-frames in the usual well known manner, of two flexible spring members secured to the spring-plank of the car truck with their ends extending upwardly and outwardly at opposite sides of the strut 20 or brake-lever post and at a suitable angle to receive, support and guide the truss-rods of the brake-beams at their end portions, during the movement of the brake-beam so as to assure a correct positioning of the 25 brake-beams and maintain a concentric relation of the working faces of the brake-shoes to the tread of the car wheels, both in the service applications of said shoes to the wheels and their release therefrom under all conditions 30 as to the wear of either the shoes or wheels, or both thereof.

Another object of my invention consists in securing the supporting spring members to the spring-plank in such a manner that they 35 will be held securely in their operative position, but will enable the supporting spring members to slide longitudinally with relation to the spring-plank to facilitate the more easy removal and replacement of the brake-beams without the removal of rivets, bolts, or 40 cotter pins or the like, whereby the building of trucks as well as making repairs to the same is greatly facilitated.

A further object of my invention resides 45 in securing chairs near the ends of the spring members for receiving and supporting the truss-rods of the brake-beams at their intermediate points, said chair being free to slide on the spring members but permanent- 50 ly secured thereto.

Having thus given a general description of my invention, I will now in order to make the same more clear, refer to the annexed one sheet of drawings, which forms part of this specification, and in which like characters 55 of reference indicate like parts:

Fig. 1 is a top plan view showing portions of the spring-plank and brake-beams in dotted lines to illustrate the application of my 60 invention;

Fig. 2 is a sectional elevation taken on the line II—II of Fig. 1, showing parts of one of the spring members broken away to more 65 clearly illustrate the construction;

Fig. 3 is a vertical transverse section of 65 one of the spring supporting members taken on the line III—III of Fig. 2;

Fig. 4 is a side elevation of one of the 70 chairs;

Fig. 5 is an end elevation of the chair;

Fig. 6 is a top plan view of the chair;

Figs. 7 and 8 illustrate in detail a modified 75 form of an abutment formed in the spring supporting members to those shown in Figs. 1 and 2; and

Figs. 9 to 12 show in detail modified forms 80 of constructing the central portion of the spring supporting members so that it may be attached to an inclined spring-plank.

Referring now to the characters of reference, and first to Figures 1 to 6 inclusive, the numeral 1 indicates the spring-plank and 85 2 the brake-beams, each comprising a truss-rod or tension member 2', 3 the compression member, and strut 4 adapted to take the usual brake-lever, not shown.

On the under side of the spring-plank 1, on each side of the transverse center line of the same is secured by means of rivets 5, a pair of keepers 6 having arc-shaped central 90 portions for supporting the spring supporting member 7. The spring supporting members are each bent upwardly to form an apex portion at the center as at 8 to contact with the longitudinal center line of the spring-plank on the underside face thereof, from which point they are bent downwardly passing through the keepers and have bosses 9, formed therein beyond the outer faces of the keepers to serve as abutments to hold the 100

spring members in their normal position and to prevent them from sliding longitudinally. The ends 10, of the spring supporting members are bent upwardly and are slotted as at 5 11 through which the lug 12 of the chair 13 extends. The lug 12 has a hole 14 formed therein for receiving a rivet 15 the extending heads of which prevent the chair from being separated from the spring members, 10 but allowing it to slide freely thereon. Each chair 13 is formed with a base 16 for slidably engaging the upper inclined face of the outer ends 10 of the spring members 7 and bifurcated extensions 17 rounded on their inner 15 faces between which is formed a socket 18 for receiving the truss-rod or tension member 2' of the brake-beam.

The brake-beam tension member rests in the sockets 18 of the sliding chairs which can move freely longitudinally on the inclined ends of the spring supporting members and maintains the brake-shoes in a concentric position with relation to the wheels at all times.

25 In case of failure of beam or hangers the spring supporting members serve the purpose of a safety device to prevent the brake beams from falling to the rails.

With my device, if it is desired to remove 30 the brake-beam after the hangers and other attachments, not shown, have been disconnected it is only necessary to raise the ends of the spring supporting members which rest on the keepers until the bosses or abutments 35 are above the edge of the keepers after which the spring supporting members can be pushed back to the position shown in dotted lines in Fig. 2 which allows the brake-beams to be lowered and removed. In this manner the 40 brake-beams can be removed without removing any rivets, cotter pins, bolts or pins.

In Figures 7 and 8 I have shown the abutments on the spring supporting members 7 formed as corrugations 19, instead of bosses 45 as illustrated in Figures 1 and 2. In Figures 9 and 10 I have illustrated spring supporting members formed with a boss 20 at the center for engaging the spring-plank which is more desirable for use when the 50 latter is inclined, and a somewhat similar construction is shown in Figures 11 and 12 in which the central portion of the spring supporting members is formed arched as at 21.

55 Although I have shown and described my invention in considerable detail, I do not wish to be limited to the exact and specific details shown and described, but may use such substitutions, modifications or equivalents thereof as are embraced within the scope of my invention or as pointed out in the claims.

Having thus described my invention what I claim and desire to secure by Letters Patent 60 is:

1. A support for brake-beams, comprising a spring-plank, keepers permanently secured to the spring-plank near each side thereof, a spring supporting member permanently secured to the spring-plank by means of the 70 keepers having a central upwardly extending apex portion between the keepers for resiliently engaging the spring-plank, downwardly inclined intermediate portions for yieldingly engaging the keepers and upwardly extending slotted end portions, sliding chairs permanently secured to the upwardly inclined slotted end portions, abutments formed in the downwardly inclined intermediate portions for normally engaging the keepers for holding the spring supporting member against longitudinal movement, the bearing surface of the keepers being spaced apart from the spring-plank to allow the abutment to slide over the keeper and out of engagement with the spring-plank when the end of the spring supporting member is raised.

2. A support for brake-beams, comprising a spring-plank, U-shaped keepers having flanged edges permanently secured to the underside of the spring-plank near each side edge, a spring supporting member permanently secured to the spring-plank by means of the keepers having a central upwardly extending apex portion for normally engaging the spring-plank between the keepers, downwardly extending intermediate portions for yieldingly engaging the keepers and upwardly extending slotted ends, sliding 90 chairs permanently secured to the slotted end portions, abutments formed in the inclined intermediate portions of the spring supporting member for engaging the keepers beyond the outer faces thereof for normally holding the spring supporting members against longitudinal movement and adapted for slidable engagement with the spring-plank and keepers when the end of the spring supporting member is raised.

3. A trussed brake-beam, spring members for supporting the intermediate portions of the brake-beams, a spring-plank, keepers permanently attached to the spring-plank for securing the spring members to the spring-plank, abutments on the spring members for normally engaging the keepers beyond the outer faces thereof for holding the spring members centrally on the spring-plank, said keepers having their bearing surfaces spaced apart from the spring-plank to allow the abutments to slide over the bearing surface of the keepers and out of engagement with the spring-plank when the end of the spring supporting member is vertically raised.

4. A support for brake-beams, comprising a spring-plank, keepers permanently secured to the bottom of the spring-plank near each side thereof, a spring supporting member permanently secured to the spring-plank by

means of the keepers, having a central upwardly extending apex portion between the keepers for engaging the spring-plank on the underside face, downwardly inclined intermediate portions for yieldingly engaging the keepers and upwardly and outwardly extending slotted end portions, sliding chairs permanently secured to the upwardly inclined slotted end portions, abutments formed in the 5 downwardly inclined intermediate portions for normally engaging the outer side face of the keepers for holding the spring supporting member against longitudinal movement, the bearing surfaces of the keepers being 10 spaced apart from the spring-plank to allow one of the abutments formed on the spring supporting member to slide over the keeper when either end is raised thereby allowing the spring supporting member to slide out 15 of engagement with the spring-plank.

5. A fourth point support for brake-beams, comprising a spring-plank, keepers permanently secured to the spring-plank, spring supporting members each having a 25 central apex portion adapted to contact with the underside face of the spring-plank, downwardly inclined intermediate portions for engaging the keepers and upwardly inclined end portions, said spring supporting 30 members being permanently secured to the spring-plank by the keepers and held centrally in position by their own resiliency, abutments formed in the spring supporting members for normally holding them against 35 longitudinal movement, said spring supporting members adapted when one end is raised to slide longitudinally on the keepers out of engagement with the spring-plank, and sliding chairs permanently secured to the spring 40 supporting members for engaging and supporting the brake-beams at intermediate points.

6. A fourth point support for brake-beams, comprising a spring-plank, keepers 45 permanently secured to the spring-plank, spring supporting members each having a central apex portion adapted to contact with the underside face of the spring-plank, downwardly inclined intermediate portions 50 for engaging the keepers and upwardly inclined slotted end portions, said spring supporting members being permanently secured to the spring-plank by the keepers and normally held centrally in position by their own 55 resiliency, bosses formed in the spring supporting members engaging the outer faces of the keepers for normally holding them against longitudinal movement but adapted for longitudinal movement when one of the 60 bosses is raised above the bearing surface of the keepers, and a sliding chair permanently secured to each of the upwardly inclined slotted ends of the spring supporting members for engaging and supporting 65 the brake-beams at intermediate points.

7. A fourth point support for brake-beams, comprising a spring-plank, keepers permanently secured to the spring-plank, spring supporting members each having a central apex portion adapted to contact with the underside face of the spring-plank, downwardly inclined intermediate portions 70 for engaging the keepers, bosses formed in the downwardly inclined intermediate portions of the spring supporting members adapted to normally engage the outer faces of the keepers and holding them against longitudinal movement but adapted for longitudinal slide movement out of engagement with the spring-plank when one of the bosses is raised above the bearing surface of the keepers, a sliding chair mounted on each of the upwardly inclined slotted ends of the spring supporting members for engaging and supporting the brake-beams at intermediate 75 points, and a lug projection formed on each of the sliding chairs extending through each slot and permanently secured to the upwardly inclined ends of the spring supporting members.

In testimony whereof I hereunto affix my signature.

LOUIS G. MILLER.
